UNITED STATES PATENT OFFICE.

NORMAN C. NISPEL, OF YORK, PENNSYLVANIA, ASSIGNOR OF ONE-HALF TO JOSEPH WILLIAMS, OF FAWN GROVE, PENNSYLVANIA.

ELECTRIC-LAMP SWITCH.

1,051,749.

Specification of Letters Patent. Patented Jan. 28, 1913.

Application filed July 16, 1912. Serial No. 709,709.

To all whom it may concern:

Be it known that I, NORMAN C. NISPEL, a citizen of the United States of America, residing at York, in the county of York 5 and State of Pennsylvania, have invented new and useful Improvements in Electric-Lamp Switches, of which the following is a specification.

This invention relates to improvements 10 in electric switches and has particular application to electric switches for use in conjunction with electric lamps.

In carrying out the present invention, it 15 is my purpose to provide a switch whereby the electric current may be fed into the lamp in a step by step manner or gradually so that the filaments of the lamp may be rendered luminous to give any desired or predetermined candle power.

20 It is also my purpose to provide an electric lamp switch wherein by means of a plurality of sections of resistance and a movable switch element, the current may be fed into the filaments of the lamp in a step by 25 step manner so as to give any desired amount of light.

Another object of my invention is the provision of an electric lamp switch which 30 will embrace the desired features of simplicity, efficiency, durability and convenience and which may be manufactured and installed at a relatively low cost.

With the above and other objects in view, the invention consists in the construction, 35 combination and arrangement of parts hereinafter set forth in and falling within the scope of the claim.

In the accompanying drawing; Figure 1 is a vertical sectional view through a switch 40 constructed in accordance with the present invention. Fig. 2 is a transverse sectional view of the same, and Fig. 3 is a diagrammatic view showing the sections of resistance arranged in the circuit and the relative 45 position of the movable switch element.

Referring now to the accompanying drawing in detail, the numeral 1 designates a shell or casing preferably of cylindrical outline and provided with an inner lining 2 50 of suitable insulating material having formed therein a longitudinally extending bore 3 designed to accommodate one of the electric current carrying conductors of the circuit, such bore being in communication 55 with a recess 4 formed in the lining adja-

cent to the lower end of the casing 1. This lining 1 is further provided with a longitudinal passage 5 arranged in parallelism with the bore and forming a guide way and arranged or embedded in one wall of the 60 passage 5 are a plurality of sections of resistance 6 each provided with a contact 7 disposed upon the face of the respective wall and within the guide way. These sections of resistance are preferably connected 65 in series with one another as illustrated in Fig. 3 and with one conductor 8 of an electric circuit, the other conductor 9 of such circuit being passed through the bore 3. If desired, the portions of the conductors 8 70 and 9 of the electric circuit within the switch may form a part of such switch and terminate at one end of the casing in a suitable form of contact member, the remaining portions of the conductors of the circuit, that 75 is to say, the portions of the conductors beyond the switch being also terminally connected to a companion contact member for the first member. The end of the switch casing or shell opposite from the end receiving the wires of the electric circuit has connected thereto in any suitable manner an ordinary form of lamp socket member 10 to which is connected the free terminal of the wire 9 of the electric circuit within the 80 switch casing.

Journaled transversely of the casing or shell through the passage way 5 therein, is an actuating shaft 11 equipped, on the outer side of the casing, with a manipulating disk 90 or wheel 12 and carrying within the passage 5 a cog pinion 13 designed to mesh with a rack bar 14 of the movable switch element, such element including the block of insulating material 15 to which the rack bar is 95 fastened, and a contact finger 16 at one end of such block and connected by way of a wire 17 with a contact plate 18 secured to the end of the shell 1 and disposed within the socket forming member 10. This contact finger 16 is designed to engage the contacts 7 of the resistance sections 6 in the circuit so as to cut the resistance sections successively out of the circuit. When the movable switch element reaches the limit 100 of its upward movement within the guide way 5, the contact finger 16 thereon engages a contact 19 connected to one wire of the electric circuit and completes the circuit to the lamp from such contact 19 by 110

way of the wire 17, thence through the plate 18, lamp filaments, socket member 10 and the wire 9, thus illuminating the lamp with all of the sections of resistance out of the 5 circuit.

From the foregoing description taken in connection with the accompanying drawing, the construction, mode of operation and manner of employing my invention will be 10 readily apparent. Assuming the lamp to be extinguished; it will be seen that the movable switch element is disposed at the lower end of the guide way or passage 5. Should it be desired to illuminate the lamp, the 15 manipulating disk or wheel 12 is rotated with the effect to rotate the shaft 11 and cog pinion 13 and so elevate the movable switch element, whereby the contact finger 16 will pass from one contact 7 to the other, 20 in the continued movement of the actuating shaft, to gradually or successively cut the resistance sections out of the circuit. The movable switch element may be held in any position to enable the lamp to give the desired or predetermined candle power and 25 in order to hold the switch element in such position, I employ a braking device which in the present instance, consists of a friction shoe 20 loosely encircling the actuating 30 shaft adjacent the manipulating wheel thereon and held in engagement with the hub of such disk or wheel by means of an expansion spring 21 surrounding the actuating shaft between the brake shoe and the 35 adjacent surface of the casing. When the movable switch element is in its lower or inoperative position, the slack in the wire 17 is disposed within the recess 4.

It will be noted that I have provided a 40 simple, yet efficient and convenient form

of electric lamp switch and one whereby the lamp may be illuminated to any desired or predetermined candle power.

While I have herein shown and described one preferred form of my invention by way 45 of illustration, I desire to have it understood that I do not limit myself to the precise details of construction herein described and delineated, as modification and variation may be made within the scope of the claim and 50 without departing from the spirit of my invention.

I claim:

The combination with a pair of electric current carrying conductors forming a circuit, of an electric lamp switch comprising a shell, a lining of insulating material within the shell and provided with a bore for one of the electric current carrying conductors, a recess contiguous the bore, and a passage parallel with the bore and forming a guide way, a plurality of resistance sections arranged in one wall of said passage and connected in series with one another and the other conductor, a switch element movable through said passage and adapted to cut the resistance sections out of the circuit, a wire leading from said switch element and adapted to be disposed in said recess, a lamp socket member secured to the shell and forming the terminals of the circuit, and means for holding the switch element in any desired or predetermined position.

In testimony whereof I affix my signature 75 in presence of two witnesses.

NORMAN C. NISPTEL.
